United States Patent Office

Des. 224,829
Patented Sept. 26, 1972

224,829

PLASTIC JAR

Ralph G. Amberg, Monticello, Ind., assignor to Owens-
Illinois, Inc., Toledo, Ohio

Filed June 4, 1971, Ser. No. 150,265

Term of patent 14 years

Int. Cl. D9—01

U.S. Cl. D9—154

FIG. 2

FIG. 1

FIG. 1 is an elevational view of a plastic jar showing my new design; and

FIG. 2 is a top plan view thereof.

The side opposite that seen in FIG. 1 is the same in appearance as the side shown.

I claim:

The ornamental design for a plastic jar, substantially as shown and described.
